Geo. N. Goddard, Atty.

UNITED STATES PATENT OFFICE.

WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed September 10, 1923. Serial No. 661,806.

This invention relates to tube frames such as are used for tuft weaving and is intended to provide a convenient, simple and strong construction for operatively suspending the tube frame and yarn spool from the usual and well known carrier chains by which the successive tube frames are presented to the transfer mechanism by which they are properly presented to the fabric being woven in the loom.

The invention embraces several features of construction and arrangement, of which one feature consists in the construction and arrangement of the suspension members of the hanger which affords easy and direct access to the spool journal without weakening the suspension hanger or sacrificing the desired degree of rigidity of parts; another feature comprises a novel construction for easily and detachably fulcruming the hook arm of the hanger in proper position. These and other features will be described in the following specification and will be defined in the claims annexed.

In the drawings I have illustrated the preferred form embodying the principles of this invention, in which,

Fig. 1 is a vertical section of the end portion of the frame and spool with the improved hanger operatively attached thereto.

Fig. 2 is an end elevation viewed from the outside.

Fig. 3 is a side elevation of the same.

Fig. 4 is a plan view.

Fig. 5 is a detail showing the attaching plate or member in perspective.

The tubular carrier bar 1 is of polygonal cross section and forms the back bone of the tube frame besides supporting the usual tuft tubes 1^a for guiding the yarn tufts. The yarn spool 2 with its axial journal 3 normally pressed outward by the helical spring 4 is of usual construction.

The suspension hanger by which the tube frame and its yarn spool are suspended from a carrier chain α comprises generally a spool supporting arm or member 5, a chain penetrating arm 7 and a hook arm 8 movable to chain engaging position in this case by an interposed spring 6 seated in a recess 5^a in the spool arm, the upper end of said hook arm being carried through an opening in the outwardly offset portion of the arm 7.

The hanger arm 7 is formed with a length-

wise medial slot or recess extending from 55 near its lower end 7^a to and into the outwardly offset or bent portion of the slot or recess being wide enough to allow the hook arm 8 to lie therein when the latter is pushed inwardly by the transfer mechanism to release the hook from the chain α . This leaves the main vertical portion of the hanger with two spaced arms astride of the swinging hook arm and these are firmly secured to the spool arm 5 in any suitable manner as by 65 spot-welding so as to produce a firm and rigid construction. The offset portion of these two branches of the hanger arm are united by a cross tie 7^b located so as not to interfere with the proper movement of 70 the hook arm, while increasing the stiffness of the hanger.

As heretofore constructed the hanger presented a serious obstacle to the easy manipulation of the spool journal which has 75 to be pushed inwardly out of engagement with its bearing orifice in the spool arm or bracket. To remedy this inconvenience I have provided aligned perforations 7^d in the hanger and 8^d in the hook arm arranged 80 opposite the bearing orifice in the upper end of the spool arm, thus permitting the operator to insert a wire through the aligned openings to press the journal inwardly when he wishes to remove the spool. As such 85 perforation of the hook arm tends to seriously weaken it for service and as its width at this point must be substantially less than that of the hanger to avoid cutting away too much stock from the hanger arm, I compensate 90 for this perforation of the hook arm by making the portion receiving the perforation substantially wider and then bending up such extensions to form stiffening ears or flanges 8^e extending at approximately 95 right angles to the plane of the arm 8, thus making the over all width of the perforated hook arm narrow enough to move between the branches of the hanger arm while preserving the requisite degree of 100 strength to secure reliability.

The composite hanger is secured firmly but detachably to the carrier bar by means of an attaching member in the form of a channel plate 9 whose side wings fit snugly 105 between the front and back walls of the carrier bar and whose middle portion is adapted to lie face to face with the inner

face of the lower end portion of the hanger. The middle portion 9^a of the attaching plate is provided with a relatively wide vertical opening or slot 9^b for the reception of the 5 reversely bent fulcral portion 8^b of the hook arm and is also formed with narrow transverse slots or notches 9^c forming bearing recesses for receiving and supporting a transverse fulcral pin 10. A single operation 10 of the stamping die forms a cross shaped opening which may be made at the same time that the hook arm is stamped out so that no extra expense is involved in forming a bearing support for the pin 10, which 15 is small enough in diameter to lie within the recess 9^c, when the parts are assembled and fastened together with rivets, screws or the like. Attaching screws 11 are passed through the front and rear walls of the carrier 20 bar and are tapped into the opposite wings of the attaching plates, thereby permitting the easy and quick removal of the hanger from the carrier bar, after which the fulcral or hook-arm pin 10 may be 25 pushed out endwise to permit removal and replacement of the hook arm.

It will therefore be seen that a hanger construction of low cost and great simplicity is provided which is capable of quick and 30 easy manipulation in use and one that is easily assembled and taken apart while at the same time securing the desired degree of rigidity and complete accuracy in respect to positioning of parts and durability and 35 reliability in service.

What I claim is:

1. In a tube frame for tuft weaving the 40 combination with a longitudinal carrier bar of suspension members therefor, a spool bearing member having a spool bearing for supporting a spool journal, one of said suspension members being provided with an opening opposite said journal bearing and having its side edges turned to form one or 45 more reinforcing lips opposite the opening, substantially as described.

2. A hook arm for a tuft tube frame embracing an elongated arm adapted at its lower end to be attached to the tube frame 50 and having a chain engaging hook at its upper end, said arm being provided intermediate of its ends with an aperture located to align with the spool bearing of the tube frame and being flanged at said apertured

portion to stiffen the apertured portion, substantially as described. 55

3. In a tube frame for tuft weaving the combination of a carrier bar, a hanger attaching member comprising a channel plate where side wings are disposed to telescope 60 inside the hollow end of the carrier bar and be secured thereto, the middle portion of said attaching member being cut away to form a hook arm receiving opening provided with opposed bearing notches, a transverse 65 pin seated in said notches, a hanger arm secured to said attaching member and a co-operating hook arm mounted on said pin for fulcral support.

4. In a tube frame for tuft weaving the 70 combination of a carrier bar, suspension means therefor embracing a chain engaging hanger arm and a pivotal hook arm provided with an inwardly projecting attaching hook at its lower end, an attaching member 75 whose middle portion is cut away to receive the said hook and afford bearings for a fulcral pin, the middle portion of said attaching member being secured to the carrier bar and a fulcral pin inserted in its bearings to 80 pivotally support the hook arm.

5. The combination with a carrier bar, a spool supporting suspension hanger, a chain engaging hook arm, an attaching member whose sides are secured to opposite walls of 85 the carrier bar and whose middle portion is secured to said hanger, both attaching member and hanger being recessed to receive the inwardly turned hook shaped lower end portion of the hook arm and a fulcral pin 90 inserted between the attaching member and the hanger and forming supporting engagement with said inwardly turned hook.

6. In a tube frame, the combination of 95 a carrier bar, a vertical spool bearing arm, a slotted hanger arm, secured face to face to said spool bearing arm, a chain engaging hook arm having an inwardly turned outwardly opening fulcral hook, an attaching plate rigidly secured to said spool and 100 hanger arms and furnished with a bearing recess, a fulcral pin mounted in said bearing to support the hook arm and means for securing the attaching plate to the carrier bar, substantially as described. 105

In witness whereof, I have subscribed the above specification.

WALTER BIXBY.
